ARC RUNNER WITH TRAP FOR PRODUCTS
OF ARCINGPhilip L. Taylor, Abington, Mass., assignor to
Allis-Chalmers Manufacturing Company, Mil-
waukee, Wis.

Application October 7, 1950, Serial No. 188,911

12 Claims. (Cl. 200—147)

1

This invention relates to circuit interrupting devices and more particularly to circuit breakers of the air break type wherein an arc established between separable contacts is transferred along arc runners into an arc extinguishing chute.

The interruption of heavy current power arcs is often accompanied by the emission of a great deal of arc products including incandescent metal particles or other inorganic substances. These particles if not confined tend to break down the dielectric strength of the surrounding air and thereby increase the time necessary to extinguish the arc, or cause failure of the circuit breaker.

In accordance with the invention claimed a new and improved circuit interrupting device is provided comprising relatively movable contacts which are actuated to initiate and elongate an arc therebetween. The arc is then transferred along a pair of spaced arc runners from the region of arc initiation to a region remote therefrom. Trap means are arranged immediately adjacent the point of arc initiation and extending along the arc runners in the direction of arc transfer for reducing, inhibiting or trapping the flow of hot or incandescent particles emitted from the arc runners into the space therebetween.

It is, therefore, one object of the present invention to provide a new and improved arc interrupting device in which the products of arcing are confined before they break down the dielectric strength of the air between the arc runners.

Another object of the present invention is to provide a new and improved arc interrupting device in which the products of arcing are trapped in a pocket defining means arranged immediately adjacent the point at which the particles were emitted.

A further object of the invention is to provide a new and improved electric circuit interrupting device in which a trap means for inhibiting the free flow of the products of arcing controls the movement of the arc along a pair of arc runners.

Objects and advantages other than those above set forth will be apparent from the following description when read in connection with the accompanying drawing, in which:

Fig. 1 is a view in cross section, of a magnetic blowout type circuit breaker employing the present invention; and

Fig. 2 is a view in cross section of a portion of the embodiment illustrated in Fig. 1 taken along the line II—II.

Referring more particularly to the drawings by characters of reference, Fig. 1 illustrates a

magnetic blowout type of circuit breaker including as elements thereof a pair of terminal studs 6 and 7 for connecting the circuit breaker to line conductors (not shown). Although in general, circuit breakers of the type considered in Figs. 1 and 2 are provided with a plurality of similar pole structures, one for each phase of a polyphase electric circuit, only one such pole structure is shown in the drawings and the circuit breaker will be described in detail as if it was of the single pole unit type.

The circuit interrupter or breaker in Fig. 1 comprises essentially means for opening the circuit to form the interrupting arc and an arc extinguishing structure. Specifically, the circuit opening means comprises fixed current carrying contact 8 and tertiary contact 9, a fixed arcing contact 10, and a movable contact 11 comprising current carrying, tertiary, and arcing contacts combined in a single structure. Arcing contact 11 is mounted on a lever 28 which is pivotally mounted at 12 on an extension 13 of the circuit breaker stud 6 and is operated by means of a reciprocally movable rod 14. The operating rod 14 is suitably connected to an actuating mechanism (not shown) for operating the movable contact between closed and open circuit positions. Fig. 1 illustrates the movable contact 11 in an intermediate position. The arcing contacts are electrically connected to the lower ends of terminal studs 6 and 7. Accordingly, when the breaker is connected in series in a power circuit and the arcing contacts are separated, an arc may form across the gap indicated.

For the purpose of interrupting this power arc, 35 an arc extinguishing structure, such as an arc chute 15 may be mounted so as to receive the power arc which is under the influence of the magnetic blowout means. The arc chute containing a stack of spaced plates of insulating material having inverted V-shaped slots defining an arc constricting groove preferably is disposed directly above the arcing contacts, as shown, when the blowout means act upward, but may be mounted in any other suitable location when the blowout means act in other directions. The switch or arcing contacts and the magnetic blowout structure can assume any preferred form so that a brief description thereof will be sufficient. The magnetic blowout means comprises a core 40 17, poles 18, and a coil 16 which is electrically connected to the terminal stud 7 and to a metallic arc runner 19 so that the arc current (as the arc travels along the runner) flows through the blowout coil in a manner well known in the art. 45 Normally the current is carried in the closed

circuit position of the breaker by the spring biased contact 8. As the movable arcing contact 11 is actuated to open circuit position, current is shunted from fixed contact 8 to fixed contact 9, to fixed arcing contact 10. As the arc is drawn by the movable arcing contact 11, the arc terminal on arcing contact 10 is transferred to arc runner 19 which is usually an extension arm of the fixed arcing contact 10. As the movable arcing contact 11 approaches or reaches its full opening stroke the arc terminal transfers from the movable arcing contact 11 to an arc runner 20 which directs the arc into the arc chute 15. One end of the blowout coil 16 is connected to the arcing contact 10 and the other end to tertiary contact 9. When the movable arcing contact 11 parts from contact 9, the flow of current is transferred from contact 9 to contact 10 through the blowout coil 16. The movable arcing contact 11 subsequently parts from contact 10 to draw an arc. Accordingly, the blowout coil is already energized at the inception of the arc to influence the arc in a well known manner, i. e. to drive it into the arc chute 15 in an expanding loop. It will be apparent to one skilled in the art that the blowout field can be utilized in the most efficient manner by disposing the iron poles 18 so as to cooperate with the blowout coil in the conventional manner outside of the arc chute.

Arc runners 19 and 20 are each provided with two sections. Arc runner 19 comprises a first section 21 arranged within arc chute 15 substantially parallel to the direction of arc transfer in a zone relatively remote from the point of arc initiation, and a second section 22 conductively connected to section 21 and arranged in an acute angular relationship with respect to the direction of arc transfer and to the first section 21 for transferring one terminal of the arc from the fixed arcing contact 10 to the first section 21. Arc runner 20 comprises a first section 23 arranged within arc chute 15 and parallel with section 21 of arc runner 19 but spaced therefrom at the opposite side of the arc chute, and a second section 24 arranged in an acute angular relationship with respect to the first section 23 and conductively connected thereto for transferring the other terminal of the arc from the movable arcing contact 11 to the first section 23.

In accordance with the invention, two trap means 25, 26 arranged substantially coextensive with at least a part of each of the arc runners 19 and 20, respectively, are provided for reducing or inhibiting the free flow of products of arcing from the arc runners in the general direction of the arc path. Trap means 25, 26 may, for example, comprise two arc chute end plates each having a pair of spaced members formed integral therewith and arranged to extend substantially coextensive with the arc runner sections 22, 24 and spaced therefrom in the direction of the arc path. The spaced members of trap means 25, 26 inhibit the free flow of incandescent particles from the arc runners to the space surrounding the arc as it is being elongated and introduced into the barrier structure of arc chute 15. Fig. 1 illustrates members 29, 31 of trap means 25, 26 and Fig. 2 illustrates a portion of members 30, 31 of trap means 26. As illustrated in Fig. 2 members 30, 31 may be spaced apart from each other to provide a passage between members and along the arc runners 19 and 20 for the arc to travel during its movement into and through arc chute 15.

The sections of arc runners 19 and 20 are pref-

erably formed by relatively wide strips of metal rather than by a pair of narrowly spaced rails. Trap means 25, 26 confine the arc roots to the center portions of the arc runners thereby resulting in a better distribution of the thermal duty of the arc runners throughout the entire width thereof.

Arc chute side walls 32, 33 are preferably provided with downward extensions forming an enclosure 34 about the contact structure to increase the chimney effect of the arc chute.

Individual barrier plates are separated a predetermined distance from each other by suitable separators, such as, for example, $\frac{1}{8}$ to $\frac{1}{4}$ inch diameter round braided asbestos rope packing 35 as illustrated in Fig. 2. The packing is covered with a suitable coating of cement to protect it from the disintegrating effects of the arc and to unite the barrier plates into a unit.

Under normal interrupting conditions an arc is initiated immediately upon separation of the arcing contacts 10 and 11. The terminal of the arc on fixed arcing contact 10 is driven over sections 22 and 21 of arc runner 19 toward the exhaust end of arc chute 15 by the magnetic blowout means and the thermal effect of the arc. As movable arcing contact 11 approaches its fully open position the other terminal of the arc jumps from contact 11 to arc runner 20 and particularly section 24 thereof and is also driven by the blowout means and the thermal effect of the arc along sections 24 and 23 toward the exhaust end of arc chute 15.

Upon initiation of the arc and also during its movement along the arc runners 19 and 20 emission of arc products including incandescent metal particles or other inorganic substances occurs which heretofore were jettisoned into the area surrounding the elongated arc. These incandescent particles reduce the dielectric strength of the air or other gas surrounding the arc, thereby increasing the possibility of reignition or restriking of the arc after it was extinguished.

The tendency of the arc to stick to the arcing contacts or arc runners is greatest at, or immediately after, the time of initial contact separation. Obviously, the velocity of arc propagation is zero at the time of initial contact separation and it takes time, however little that time may be, to move the arc roots away from the points on the arcing contacts where they are initially formed. Because of the time required to accelerate the motion of the arc roots along the arc runners, the region of worst gap contamination by arc products is that immediately adjacent the point of initial separation of the contacts. It is, therefore, important that trap means 25 be arranged at or immediately adjacent this particular point. Likewise, trap means 26 is arranged at or immediately adjacent the point of initial arcing on arc runner 24.

The new improved trap means 25, 26 being disposed immediately adjacent the point of arc initiation, inhibit the free flow of the arcing products from their source, namely the arc terminals, toward the zone occupied by the elongated arc. As the power current flows through the arc, the arc products are emitted in all directions from the areas occupied by the arc terminals as they move across the sections of the arc runners. By mounting the sections of trap means 25, 26 immediately adjacent the arc runners 19 and 20 in the manner described, the rate of flow of arc products into the space between the arc runners where there is potential danger of reignition and restriking is

controlled. Reignition usually occurs substantially along the path which the arc occupied previous to current zero and restriking usually occurs in the arc chute where the gap between the arc runners is relatively short. Thus, the arc products are confined in the pockets formed between the arc runners and the members of trap means 25, 26 to preserve the dielectric strength of the gases surrounding the elongated arc to prevent reignition and restriking.

Although but one embodiment of the present invention has been illustrated and described, it will be apparent to those skilled in the art that various changes and modifications may be made therein without departing from the spirit of the invention or from the scope of the appended claims.

It is claimed and desired to secure by Letters Patent:

1. An electric circuit interrupter comprising a pair of relatively movable cooperating arcing contacts, means for separating said contacts to initiate and elongate an arc therebetween, arc runners for transferring said arc from the region of arc initiation to a region remote therefrom, said arc runners comprising a first section arranged substantially perpendicularly to the direction of relative movement of said contacts and spaced from the region of arc initiation and a second section arranged angularly with respect to said first section for transferring one terminal of said arc from the region of arc initiation to said first section, and trap means arranged substantially coextensive with said second section for reducing the free flow of products of arcing from said second section in the general direction of the arc path.

2. An electric circuit interrupter comprising a pair of relatively movable cooperating arcing contacts, means for separating said contacts to initiate and elongate an arc therebetween, an arc runner for transferring said arc from the region of arc initiation to a region remote therefrom, said arc runner comprising a flat metallic member arranged angularly with respect to the direction of movement of the arcing contacts, and trap means comprising two flat insulating members mounted substantially coextensive with said flat metallic member for inhibiting the free flow of products of arcing from said arc runner in the general direction of arc transfer, said insulating members separated from each other to provide a passage for the arc to travel along the arc runner between said insulating members in the direction of arc transfer.

3. An electric circuit interrupter comprising a pair of relatively movable cooperating arcing contacts, means for separating said contacts to initiate and elongate an arc therebetween, an arc chute for receiving the arc at one end thereof and exhausting the hot gases at the other end, arc runners for transferring said arc from the region of arc initiation into said chute, said arc runners comprising a first section arranged within said arc chute substantially perpendicularly to the direction of relative movement of said contacts and a second section arranged adjacent said arcing contacts angularly with respect to said first section for transferring one terminal of said arc from the region of arc initiation to said first section, and trap means comprising two flat insulating members mounted substantially parallel with said second section of said arc runners for inhibiting the free flow of products of arcing from said arc runners, said insulating members being

separated from each other to provide a passage for the arc to travel along the arc runner between said insulating members in the direction of arc transfer.

5. An electric circuit interrupter comprising a pair of relatively movable cooperating arcing contacts, means for separating said contacts to initiate and elongate an arc therebetween, an arc chute for receiving the arc at one end thereof and exhausting the hot gases at the other end, arc runners for transferring said arc from the region of arc initiation into said chute, said arc runners comprising a first pair of sections mounted within said chute and longitudinally thereof for transferring the terminals of the arc through at least a part of said chute, and a second pair of sections arranged adjacent said arcing contacts for transferring the terminals of the arc from the arcing contacts to said first pair of sections, magnetic blowout means for driving the arc into said chute and toward the exhaust end thereof, and trap means comprising two pairs of flat insulating members, each pair mounted substantially coextensive with one of said second pair of sections for collecting the products of arcing from said arc runners, said insulating members of each pair being separated from each other to provide a passage for the arc to travel along said second pair of sections between said members in the direction of arc transfer.

5. An electric circuit interrupter comprising a pair of relatively movable cooperating arcing contacts, means for separating said contacts to initiate and elongate an arc therebetween, an arc chute comprising a pair of side walls mounted for receiving the arc at one end thereof and exhausting the hot gases at the other end, arc runners for transferring said arc from the region of arc initiation into said chute, said arc runners comprising a first pair of sections mounted within said chute longitudinally thereof for transferring the terminals of the arc through at least a part of said chute, and a second pair of sections arranged adjacent said arcing contacts for transferring the terminals of the arc from the arcing contacts to said first pair of sections, magnetic blowout means for driving the arc into said chute and toward the exhaust end thereof, and trap means comprising two pairs of flat insulating members attached to the said side walls of said arc chute, the insulating members of each pair being spaced apart from and mounted substantially coextensive with one of said second pair of sections for collecting the products of arcing from said arc runners, said insulating members of each pair being separated from each other to provide a passage for the arc to travel along said second pair of sections between said members in the direction of arc transfer.

6. An electric circuit interrupter comprising a pair of relatively movable cooperating contacts, means for separating said contacts to draw an arc therebetween, means including a pair of spaced arc runners for transferring said arc from the region of initial contact separation to a region remote therefrom, and trap means arranged immediately adjacent the point of initial contact separation and extending along said pair of arc runners in the direction of arc transfer for reducing the flow of products of arcing into the space between said arc runners.

7. An electric circuit interrupter comprising a pair of relatively movable cooperating arcing contacts, means for separating said contacts to initiate and elongate an arc therebetween, an

arc chute for receiving the arc at one end thereof and exhausting the hot gases at the other end, spaced insulating barriers mounted within said chute to extend transversely of the arc, one end of said barriers being disposed adjacent the zone of arc initiation, an arc runner for transferring said arc from the region of arc initiation into said arc chute, said arc runner comprising a first section arranged relatively remote from the point of arc initiation and a second section arranged relatively close to the point of arc initiation, and trap means for reducing the free flow of arc products in the direction of arc transfer comprising two flat insulating members mounted substantially coextensive with said second section and two further flat insulating members forming a part of one of said barriers and extending adjacent to and substantially coextensive with said first section.

8. An electric circuit interrupter comprising a pair of relatively movable cooperating contacts, means for separating said contacts to draw an arc therebetween, means including a pair of spaced arc runners for transferring said arc from the point of initial contact separation to a region remote therefrom, and means for reducing the flow of dielectric contaminants evolving from arc terminals into the space between said pair of contacts and said pair of arc runners, said means being arranged adjacent the point of initial contact separation and coextensive with at least a portion of one of said pair of arc runners.

9. An electric circuit interrupter comprising a pair of relatively movable cooperating contacts, means for separating said contacts to draw an arc therebetween, means including a pair of spaced arc runners for transferring said arc from the point of initial contact separation to a region remote therefrom, and means for reducing the flow of conductive products of arcing from said pair of contacts and said pair of arc runners into the space between said pair of contacts and said pair of arc runners, said flow reducing means extending substantially from the point of initial contact separation to the points on said pair of arc runners forming the ultimate terminals of the arc.

10. An electric circuit interrupter comprising a pair of relatively movable cooperating contacts, means for separating said contacts to draw an arc therebetween, an insulating structure for lengthening and cooling said arc to cause extinction thereof, arc propelling means for transferring said arc from the point of initial contact separation into said insulating structure, said arc propelling means including means for producing a transverse magnetic field and a pair of spaced arc runners on opposite sides of said insulating

structure, and means for reducing the flow of conductive products of arcing from said pair of contacts and said pair of arc runners into the space between said pair of contacts and said pair of arc runners, said flow reducing means being coextensive with at least a portion of each of said pair of arc runners situated relatively close to said point of initial contact separation.

11. An electric circuit interrupter comprising a pair of relatively movable cooperating contacts to draw an arc therebetween, a stack of spaced plates of insulating material having inverted V-shaped slots defining an arc constricting groove, means including a pair of spaced arc runners for transferring said arc from the point of initial contact separation into said groove, each of said pair of arc runners comprising a slanting portion arranged relatively close to the open end of said groove and a portion substantially parallel to the plane of one of the end plates of said stack and arranged relatively close to the closed end of said groove, and means for trapping and deionizing conductive products of arcing generated at the surface of said pair of contacts and at the surface of said pair of arc runners to reduce the quantity of said products entering the space between said pair of contacts and said pair of arc runners, said trapping means being arranged immediately adjacent said point of initial contact separation and coextensive with at least said slanting portion of each of said pair of arc runners.

12. An electric circuit interrupter comprising a pair of relatively movable cooperating contacts, means for separating said contacts to draw an arc therebetween, means including a pair of spaced arc runners for transferring said arc from the region of initial contact separation to a region remote therefrom, and trap means arranged immediately adjacent the point of initial arcing on said spaced runners and extending along said pair of arc runners in the direction of arc transfer for reducing the flow of products of arcing into the space between said arc runners.
